LUGGAGE BAG

Julia R. Rosenblum, 6 W. 77th St.,
New York, N.Y. 10024

Filed June 23, 1972, Ser. No. 265,885

Term of patent 14 years

Int. Cl. D3—01

U.S. Cl. D87—5 G

FIG. 1 is a front perspective view of a luggage bag showing my new design;

FIG. 2 is a front elevation view; and

FIG. 3 is a top plan view thereof.

The rear is a mirror image of the front without the smaller compartment and the side not shown is substantially a mirror image of the side shown.

I claim:

The ornamental design for a luggage bag, as shown and described.
